Primary Examiner — Derrick Holland(74) *Attorney, Agent, or Firm* — J. Douglas Wells(57) **CLAIM**

The ornamental design for a remote ballast, as shown and described.

DESCRIPTION

FIG. 1 is a perspective view of a remote ballast showing my new design;

FIG. 2 is another perspective view of the remote ballast shown in FIG. 1;

FIG. 3 is a front elevation view of the remote ballast shown in FIG. 1;

FIG. 4 is a rear elevation view of the remote ballast shown in FIG. 1;

FIG. 5 is a top plan view of the remote ballast shown in FIG. 1;

FIG. 6 is a bottom plan view of the remote ballast shown in FIG. 1;

FIG. 7 is a right side view of the remote ballast shown in FIG. 1;

FIG. 8 is a left side view of the remote ballast shown in FIG. 1; and,

FIG. 9 is an exploded perspective view of the remote ballast, as shown in FIG. 2.

The broken lines shown represent unclaimed subject matter and form no part of the claimed design.
